UNITED STATES PATENT OFFICE

ADOLFO POUCHAIN, OF TURIN, ITALY

NEGATIVE ELECTRODE FOR ELECTRIC ACCUMULATORS

Application filed July 8, 1931, Serial No. 549,504, and in Italy July 16, 1930.

The present invention relates to negative electrodes for zinc-lead accumulators and comprises an electrode of such class consisting of a divided metal support on which zinc is deposited during the accumulator charging operation and of a rigid metal frame on which said support is mounted, said frame connecting the outer circuit directly with the two lateral edges of said support for zinc.

10 The present invention has for its object an electrode of this kind in which the support intended to receive the zinc deposit consists of a gauze, net or grid of crossing or interwoven metal wires, said gauze, net or grid being connected at least with two lateral portions of the conducting frame and being separated from the frame portion where the connector for connection with outer circuit is fastened.

15 20 Owing to the provision of a rigid frame for carrying said gauze or grid support, this gauze or grid may consist of wires of very small gauge, this provision enabling the electrode to be made exceedingly light while securing a large area for contact of the same with the electrolyte.

On the annexed drawing are illustrated by way of example two embodiments of the negative electrode according to this invention, and

Figure 1 is a front view of a complete electrode;

Figure 2 is a front view of a modification, with parts removed.

25 In said figures, 1 is a conducting frame consisting by way of example of a length of metal wire bent in the shape of a four-side loop and having its ends connected with each other. One side of this frame and more particularly the side which is intended to be at the top when the electrode is in operative position in the accumulator, has a wing 2 fastened thereon in any approved manner, as by being cast or moulded thereon, said wing providing a connector for connection with outer circuit.

50 Two opposed edges of a piece 3 of metal wire gauze, net or grid are fastened on the sides of said support frame 1 which are intended to be vertical when the electrode is

in its normal operative position in the accumulator; said edges are fastened on said frame sides say by being wound and soldered thereon.

The lower edge of said wire gauze piece 3 may also be connected with the bottom side of frame 1, or such a bottom side of frame 1 could be omitted and then the frame 1 will be restricted to a top and two lateral sides.

55 60 The top edge of the wire gauze piece 3 is on the contrary separated or spaced from the top side of the frame 1.

In the construction of Figure 2 the metal frame 1 is covered with a strip of insulating material, as rubber, which may consist of a strip 4 bent to U-shape and affixed on the frame 1 it extending inwardly to cover also the adjacent portions of the wire gauze piece 3. The portion of said strip 4 which is in register with the top side of frame 1 thus engages the said frame with the adjacent edge of the gauze or grid piece 3 and bridges the gap intermediate them while securing their electrical insulation from each other; then the electrode provides a continuous and even 70 surface and the top edge of the gauze or grid piece 3 is engaged and firmly held and also safely insulated from the top side of the frame 1.

75 80 By the described construction, a throughout uniform and regular distribution of current is secured over the whole extent of said support grid 3 because of its connection with the sides of the frame 1 with exception of the side thereof carrying the connector 2 for connection with outer circuit.

85 90 It is useful to provide corrugations 5 (Figure 2) in the metal wire gauze or grid 3 such corrugations being conveniently made along closed lines; they may be easily secured by a die-pressing or moulding operation. Conveniently said corrugations have such a thickness or span as to impart to corrugated portions of said gauze or net a thickness substantially equal to that of the frame 1; this provision prevents deformations and warping of the electrode when it is located intermediate the cooperating separators usually embodied in accumulators.

95 100 The metal gauze or net piece 3 may be of

copper, brass, or any other metal being a good conductor of electric current and it is covered over its whole active surface with a layer of zinc which is obtained by electrolytic deposition.

What I claim as my invention and desire to secure by United States Letters Patent is:—

1. A negative electrode for the deposition of zinc during the charge in zinc-lead electric accumulators, comprising a conducting frame, a circuit connector on said frame, and a wire gauze mounted in said frame, said wire gauze having a portion of its edge connected with said frame and being separated from it in its portion adjacent to said connector.

2. A negative electrode for the deposition of zinc during the charge in zinc-lead electric accumulators, comprising a conducting frame, a circuit connector on said frame, and a corrugated wire gauze mounted in said frame, said wire gauze having a portion of its edge connected with said frame and being separated from it in its portion adjacent to said connector.

3. A negative electrode for the deposition of zinc during the charge in zinc-lead electric accumulators, comprising a conducting frame, a circuit connector on said frame, a wire gauze mounted in said frame, said wire gauze having a portion of its edge connected with said frame and being separated from it in its portion adjacent to said connector, and an insulating strip bridging said separated gauze edge and frame portion.

4. A negative electrode for the deposition of zinc during the charge in zinc-lead electric accumulators, comprising a conducting frame, a circuit connector on said frame, a wire gauze mounted in said frame, said wire gauze having a portion of its edge connected with said frame and being separated from it in its portion adjacent to said connector, and an insulating strip embracing said frame and adjacent peripheral portion of said gauze.

5. A negative electrode for zinc lead electric accumulators comprising a conducting frame, a circuit connector on said frame, a wire gauze having corrugations extending along closed lines and supported on said frame, the edge of said gauze adjacent to said connector being separated from said frame.

6. A negative electrode for zinc lead electric accumulators comprising a conducting frame, a circuit connector on said frame, a wire gauze having corrugations extending along closed lines and supported on said frame the edge of said gauze adjacent to said connector being separated from said frame, and an insulating strip embracing said frame and peripheral portions of said gauze adjacent thereto.

7. A negative electrode for the deposition of zinc during the charge in zinc lead electric accumulators comprising a four-side con-

ducting frame, a circuit connector on one side of said frame, a four-side piece of wire gauze having two sides connected with said frame, the connector-bearing side of said frame being separated from adjacent side of 70 said wire gauze piece.

8. A negative electrode for the deposition of zinc during the charge in zinc-lead electric accumulators comprising a four-side conducting frame, a circuit connector on one side of said frame, a four-side piece of corrugated wire gauze having two sides connected with said frame, the connector-bearing side of said frame being separated from adjacent side of 75 said wire gauze piece.

9. A negative electrode for the deposition of zinc during the charge in zinc lead electric accumulators comprising a four-side conducting frame, a circuit connector on one side of said frame, a four-side piece of wire gauze 85 having three sides connected with said frame, the connector-bearing side of said frame being separated from adjacent side of said wire gauze piece.

10. A negative electrode for the deposition of zinc during the charge in zinc lead electric accumulators comprising a four-side conducting frame, a circuit connector on one side of said frame, a four-side piece of wire gauze having two sides connected with said frame, the connector-bearing side of said frame being separated from adjacent side of 90 said wire gauze piece, and an insulating strip 95 embracing said frame and adjacent peripheral portion of said gauze and bridging the 100 gap intermediate said separated gauze edge and adjacent frame portion.

11. A negative electrode for the deposition of zinc during the charge in zinc lead electric accumulators comprising a four-side conducting frame, a circuit connector on one side of said frame, a four-side piece of corrugated wire gauze having two sides connected with said frame, the connector-bearing side of said frame being separated from adjacent side of 105 said wire gauze piece, and an insulating strip 110 embracing said frame and adjacent peripheral portion of said gauze and bridging the gap intermediate said separated gauze edge and adjacent frame portion.

In testimony whereof I have signed my name to this specification.

ADOLFO POUCHAIN.
